UNITED STATES PATENT OFFICE

PHILIP W. PRATT, OF BOSTON, MASSACHUSETTS.

DESIGN FOR AN ELASTIC TIRE.

42,526.

Specification for Design.

Patented May 14, 1912.

Application filed November 10, 1911. Serial No. 659,661. Term of patent 14 years.

To all whom it may concern:

Be it known that I, PHILIP W. PRATT, a citizen of the United States, residing at Boston, in the county of Suffolk and State of Massachusetts, have invented a new, original, and ornamental Design for Elastic Tires, of which the following is a specification, reference being had to the accompanying drawing, forming part thereof, on which—

Figure 1 is a plan view of a part of an elastic tire showing my new design; Fig. 2 is a side view thereof.

Referring to the drawing, 10 designates a tire having its tread curved longitudinally and laterally and provided with a plurality of longitudinally arranged staggered ribs 11, 12, the ribs 11 being longer than the ribs 12. A series of ribs 11 is arranged transversely of the tread and a similar series of

ribs 12 is also arranged transversely of the tread, as shown. The ribs are also provided with an angular contour by converging the longitudinal sides 13 to form a sharp edge 14 at the middle and extending longitudinally of the rib. The ends of each rib are also formed with inclined converging faces 15 which unite to form a sharp edge 16, which is in effect a continuation of the edge 14. The inclined ends of the ribs 11 and 12 form a plurality of diamond shaped recesses or depressions.

I claim:

The ornamental design for an elastic tire as shown and described.

PHILIP W. PRATT.
